UNITED STATES PATENT OFFICE.

JOHN C. JOHNSON, OF UNIONTOWN, PENNSYLVANIA.

DESIGN FOR A COMBINATION-TOOL MEMBER.

SPECIFICATION forming part of Design No. 31,038, dated June 20, 1899.

Application filed January 18, 1899. Serial No. 702,588. Term of patent 7 years.

To all whom it may concern:

Be it known that I, JOHN C. JOHNSON, a citizen of the United States, residing at Uniontown, in the county of Fayette and State of Pennsylvania, have invented and produced 5 a new and useful Design for a Combination-Tool Member, of which the following is a specification, reference being had to the accompanying drawings, in which—

10 Figure 1 is a perspective view of a tool constructed in accordance with my design. Fig. 2 is a side elevation.

Referring to the drawings, A represents the body portion, which consists of an elongated 15 bar tapered to a point A'. At the other end of the body portion is a shoulder B, adjacent to which is an upwardly-curved serrated recess B'. Projecting from the shoulder B is a flat reduced circular portion C, and project- 20 ing from this reduced portion is an enlarged right-angular extension D, having a serrated

notch D' in its upper face, and the upper edge is designed to extend for a short distance in a horizontal plane and thence downward at an angle less than a right angle, as 25 shown at C'. The front face D² of this extension is flat and straight, while the lower face presents a right-angled surface to the front face and is bifurcated, as at D³. The inner face of the extension is curved at an 30 angle less than that of a circle, as shown at E, terminating in a straight flat surface E' where it meets the circular portion C.

Having thus fully described my invention, what I claim as new, and desire to secure by 35 Letters Patent of the United States, is—

The design for a combination-tool member, substantially as shown and described.

JOHN C. JOHNSON.
